[57] CLAIM

The ornamental design for a combined winch and support for securing a ladder, substantially as shown and described.

DESCRIPTION

FIG. 1 is a perspective view of a combined winch and support for securing a ladder showing my new design; FIG. 2 is a front elevational view thereof on a reduced scale looking in the direction of arrow 2 in FIG. 1 with the crank handle in an alternative position; FIG. 3 is a right side elevational view of FIG. 2; FIG. 4 is a rear elevational view of FIG. 2; FIG. 5 is a left side elevational view of FIG. 2; FIG. 6 is a bottom plan view of FIG. 2; and FIG. 7 is a top plan view of FIG. 2.
